UNITED STATES PATENT OFFICE

WALTHER FRIEDELAENDER, OF RIDGEWOOD, NEW JERSEY

APPARATUS FOR AND METHOD OF PRINTING OR EMBOSsing PENCILS

Application filed December 18, 1929. Serial No. 414,860.

This invention relates generally to the manufacture of pencils, penholders and the like and has particular reference to printing or embossing advertising and similar matter upon the pencils.

One object of the invention is to provide a process for printing or embossing around the entire circumference of a pencil or the like at a single operation.

10 Another object of the invention is to provide an improved apparatus for printing or embossing around the entire circumference, or at any part thereof, of a pencil or the like. An incidental object is to provide a simple, 15 sturdy mechanism which can be operated efficiently at high speed and with a minimum risk of damaging the work or interference with effective operation of the apparatus.

Other objects and advantages will become 20 apparent from the specification hereinafter given, that specification including a description of a preferred embodiment of an apparatus shown in more or less detail in the drawings which accompany and form a part of 25 this specification.

In said drawings:

Fig. 1 represents a right side elevation of the mechanism with the nearest main side frame broken away and other parts in section to give a clear showing of some of the details.

Fig. 2 is a plan view taken substantially on the line 2—2 of Fig. 1.

Fig. 3 is a front view of the mechanism 35 with a part of the lower frame cut away to expose to view some of the parts in the lower portion of the machine.

Fig. 4 is a detail on an enlarged scale of some of the parts shown in Fig. 3.

40 Figs. 5, 6 and 7 show the work carrying table in different positions with respect to the printing or embossing die and the way in which the work is brought into cooperation with that die.

Fig. 8 is a top plan view on the line 8—8 of Fig. 3 of the work feeding mechanism and parts immediately associated therewith.

Fig. 9 is a section along the line 9—9 of Fig. 4.

50 The machine shown in the drawings is in-

tended to set on a table or stand (not illustrated) so as to hold the mechanism at a convenient working level. The machine includes a base plate 15 and side plates 16 connected by cross members 17 to give a rigid support 55 for the mechanism. Secured to the upper edges of the side plates 16 are bearing members 19 in which are journaled a shaft 20.

At one end this shaft 20 has a sprocket 21 engaged by a chain 22 transmitting to the 60 sprocket 21 power from a motor or other source of power supply. Secured to the other end of the shaft 20 is a pinion 23 meshing with a large gear 24 fastened to a shaft 25. This shaft is journaled in members 26 and has attached to it driving sprockets and an interrupted gear referred to in detail later on. The relations of the pinion 23 and gear 24 are in the nature of a speed reduction connection to prevent a motor or other high speed transmission from operating the mechanism at an excessive speed.

The interrupted gear above referred to is shown at 28 in the drawings and drives a work supporting table 29 in one direction. 75 For this purpose the table is provided with a rack 30 on its upper surface in the plane of movement of the interrupted gear 28. The table 29 is supported on four rollers 32, there being a pair at each side of the table. 80 All four rollers loosely supported on two rods 33 mounted in the side plates of the framework. When all of the parts are in their home positions the two forward rollers 32 are engaged by cuts or depressions 31 85 in the lower surface of the table.

When the shaft 25 is rotated in the direction of the arrow, Fig. 1, the interrupted gear 28 will act against the rack 30 to draw the table 29 rearward against a spring 34, 90 Fig. 2, attached to the left hand side frame of the apparatus and flex the spring. As the teeth of the interrupted or partial gear 28 pass out of engagement with the rack 30 the spring 34 will throw the table 29 forward to 95 its original position. Shortly after the rearward movement of the table by the partial gear 28 and rack 30 is started the cuts 31 will be carried past the forward rollers 32 and cause the front portion of the table 29 to be 100

roll the pencil across the face of the die. The start of this rolling movement is indicated in Fig. 5. As the table reaches the end of its rearward stroke an inclined surface 83 is brought under the pencil so that it is relieved from pressure and allowed to drop into any convenient receptacle for the completed articles. This drop is facilitated as shown in Fig. 7 by the re-engagement of the cuts 31 10 in the table with the rollers 32.

While the apparatus shown and described is in itself novel and highly suitable for carrying out the process or method, that apparatus is capable of various modifications and 15 changes and the process may obviously be practiced by other means. It is not, therefore, the desire to be limited to the disclosure herein made of either the apparatus or the process except as such limitations may appear 20 in the claims which follow.

What is claimed is:

1. In an apparatus of the character described, the combination of a support for the work, a heated die, a reciprocating member 25 for feeding pencils and the like to the work support adjacent the die, and means comprising a cam rotating on an axis parallel to the line of movement of the reciprocating member for effecting movements of said 30 member.

2. In an apparatus of the character described, the combination of a support for the work, a heated die, a reciprocating member for feeding pencils and the like to the work 35 support adjacent the die, and means comprising a cam rotating on an axis parallel to the line of movement of the reciprocating member for effecting and controlling the reciprocations of said member.

40 3. In an apparatus of the character described, the combination of a support for the work, a type carrying die, a reciprocating member for feeding the pencils to the work support, devices for effecting a relative movement of the work support and die in such a manner as to roll the pencil between the support and the die, and means comprising a cam rotating on an axis parallel to the line of movement of the reciprocating member for 45 effecting the movements of said member.

4. In an apparatus of the character described, the combination of a support for the work, a heated die, means for feeding pencils to the work support, devices for effecting a 55 relative movement of the die and work support to roll the pencils between the die and support, a carrier strip for a marking material crossing the face of the die, and devices for automatically feeding said carrier strip 60 a step between each pencil rolling operation.

5. In an apparatus of the character described, the combination of a heated die, means for rolling pencils across the face of the die, a foil carrier strip across the face of 65 the die, and devices for automatically feed-

ing said strip a step relative to the die between each pencil rolling operation.

6. In an apparatus of the character described, a heated die and a work support relatively movable to roll pencils between them, a 70 hopper for pencils, devices for moving the pencils one at a time endwise to deposit them on the work support, a foil carrier strip across the face of the die, and devices for automatically feeding said strip a step between each 75 relative movement of die and work support.

7. In an apparatus of the character described, a heated die and work support relatively movable to roll pencils between them, a hopper for holding a supply of pencils, devices for moving the pencils one at a time endwise to deposit them on the work support, a foil carrier strip across the face of the die, devices for automatically feeding said strip 80 a step between each relative movement of the die and work support, and means for regulating the length of said feeding movements.

In testimony whereof I hereto affix my signature.

WALTHER FRIEDLAENDER.
